UNITED STATES PATENT OFFICE.

HERMAN THEODORE SCHLEGEL, OF AKRON, OHIO, ASSIGNOR, BY DIRECT AND MESNE ASSIGNMENTS, OF THREE-FOURTHS TO ALBERT A. SCHLEGEL AND MICHAEL J. GILBO, BOTH OF SAME PLACE.

ELECTRIC ACTUATING MECHANISM FOR CLOCKS.

SPECIFICATION forming part of Letters Patent No. 440,241, dated November 11, 1890.

Application filed September 6, 1889. Serial No. 323,182. (No model.)

To all whom it may concern:

Be it known that I, HERMAN THEODORE SCHLEGEL, a citizen of the United States, residing at Akron, in the county of Summit and State of Ohio, have invented a new and useful Actuating Mechanism for Clocks, of which the following is a specification.

This invention has relation to electric time-keepers, and among the objects in view are to provide a motor which shall be of simple construction and consist of as few parts as possible, and which is adapted to impart an intermittent movement to a train of clock-gearing.

With these general objects in view the invention consists in certain features of construction, hereinafter specified, and particularly pointed out in the claims.

Referring to the drawings, Figure 1 is a front elevation of a motor constructed in accordance with my invention, with a portion of the outer plate forming the casing thereof removed. Fig. 2 is a rear view, the rear plate removed. Fig. 3 is a side elevation; Fig. 4, an enlarged detail, in side elevation, of the contact-points and their adjacent mechanism.

Like numerals indicate like parts in all the figures of the drawings.

The case for supporting and inclosing the mechanism hereinafter referred to consists of opposite plates 1 and 2, the latter being the front plate, and between the plates are interposed spacing-sleeves 3 at any desired points.

4 represents an electro-magnet, which is secured and supported upon the rear plate 1 by means of screws 5 passing through the plate.

6 represents an arbor which is connected with the clock-gearing in any suitable and usual manner, and upon the same is mounted a ratchet-wheel 7 and a toothed gear 8, having a hub 9, from which extends an arm 10, engaging a pin 11, projecting laterally from the ratchet-wheel, whereby any movement of the ratchet-wheel will be transmitted to the gear 8. The gear 8 is rigid with the arbor 6, while the ratchet 7 is loose thereon.

The ratchet 6 by means of the arm 10 and pin 11 operates the gear 8 and consequently

the arbor. Yet at the same time the arbor 50 has independent movement of the ratchet and moves independently when the hands of the clock are moved for the purpose of "setting" the clock.

From the base of the core of the electro-magnet there projects a bearing 12, in which by bearing-pin 13 is mounted a lever 14, from which there projects at a right angle thereto an arm 15, the end of which terminates near the upper end of the magnet 4 and abuts 6c in its oscillations alternately against a pole-piece forming a stop 16, and a set-nut 17, threaded on screw 18, extending from the stop 16. By this construction it will be apparent that the vibrations of the rock-arm 15 may be 65 regulated by an adjustment of the thumb-nut 17.

The rocking lever 14 is provided near its outer end with a counterbalancing-weight 19 and with a binding-post 20, in which is secured one of the terminals 21 of the magnetic wire. The post 20 also carries an adjustable contact-point 22.

From the free end of the rocking lever 14 there projects at a right angle thereto a horizontal arm 23, pivoted in the end of which is a toothed pawl 24, the tooth of which engages with the ratchet-wheel 7, and is maintained normally in engagement by a flat spring 25, secured to the arm 23 and terminating against 80 the pawl.

26 represents a rock-shaft mounted between the plates 1 and 2 and transversely above the ratchet-wheel 7, and fixed upon the shaft is a depending counter catch or pawl 85 27, the free end of which operates in the ratchet-wheel 7 a few teeth above the pawl 24.

28 represents a flat spring secured to and depending from a binding-sleeve 3, located above the rock-shaft 26, the free end of the 90 spring terminating against the rear face of the counter catch or pawl 27 and normally maintaining said catch in mesh with the wheel 7.

29 represents a bar provided with a binding-post 30, which receives the wire terminal 31, tied to one of the poles of a battery, the remaining wire 21 leading to the magnet. 95

The bar 29 depends from the rock-shaft 26, and a flat spring 32, slotted as at 33, is secured to the bar by set-bolts 34. The lower end of the spring, or what is in reality a flexible blade, is provided with platinum plate 35, which takes contact with the contact-point 22, which closes the circuit of the pile.

The counter catch or pawl 27, it will be observed, has two functions—namely, to prevent a retrograde movement of the ratchet 7 when drawn down and released by the pawl 24, and to produce an oscillation of the rock-shaft 26, which, it will be apparent, will have the effect of making and breaking contact between the contact-plate 35 and the contact-point 22, and thus cause an intermittent pulsation of electricity through the circuit in which is located the electro-magnet 4.

The operation is as follows: At the time that the rocking lever 14 is at the lower end of its movement the electrical contact is established between the plate 35 and the contact-point 22, and when in such position the current coming from the terminal wire 31 passes through the bar 29, the spring-blade 32, the plate 35, the contact-point 22, and the wire 21 back to the magnet, and through the magnet which magnetizes the pole 16 and attracts the free end of the rock-arm 15, thus oscillating the lever and bringing it in contact with the magnetized stop or pole and raising the rocking lever 14, and through the terminal wire 31 to the battery. This vertical raising of the rocking lever 14 raises the pawl 24 one tooth in advance of the ratchet-wheel 7, so that at a subsequent drop of the rocking lever 14 said ratchet-wheel is operated one tooth. As the wheel is operated by the pawl 24, the holding-pawl 27 is naturally oscillated by the contour of the tooth against which it rests, which oscillation rocks the shaft 26 and raises the contact-point 35 and drops into the next tooth. When the point 35 is raised, the circuit is broken between the plate 35 and point 32, and thus the electric circuit is broken. The rock-arm 15, not being attracted by the now non-magnetized stop 16, is caused by the counterbalancing-weight 19 to fall or vibrate, which acts to re-establish the circuit through the plate 35 and point 22. The duration of each vibration of the vibratory rock-arm 15 may be regulated by the weight 19, which is adjustable on the rocking lever 14, and through the medium of the set-nut 17, the distance in which the vibratory arm 15 travels is also regulated in accordance with the strength of the electric current.

The parts are so regulated that the passing of a tooth consumes one minute of time, and the entire mechanism, it will be understood, will be controlled and regulated by any ordinary horological escapement.

Having thus described my invention, what I claim is—

1. In an actuating mechanism for clocks, the combination, with an electro-magnet and its pole and an electrical circuit, of a rocking le-

ver having a vibratory rock-arm extending rigidly therefrom and having intermittent contact with the pole, a contact-point mounted on the rocking lever, and an electric terminal connected with the point and to one of the poles of the magnet, a contact-plate, and means for oscillating the same, said plate being connected with the opposite terminal of the electric wire and adapted for contact with the point of the arm, substantially as specified.

2. In an actuating mechanism for clocks, the combination, with an electro-magnet arranged in a circuit, of a rocking lever having a vibratory rock-arm rigidly mounted thereon for intermittent contact with the pole of the magnet, a contact-point, and a weight mounted on the rocking lever, and an electric terminal connected with the contact-point, a contact-bar having a plate, and means for oscillating the same, and a binding-post mounted on the bar and connected with the opposite electric terminal, the plate of the bar being adapted for contact with the contact-point of the rocking lever, substantially as specified.

3. The combination, in an actuating mechanism for clocks, of a hand-supporting arbor, a fixed gear mounted on the arbor, a ratchet-wheel for rotating the gear, a pawl for operating the ratchet-wheel, a rocking lever for supporting the pawl, a binding-post and contact-point mounted on the rocking lever, and a weight also mounted on the lever, a rock-arm projecting from the lever, an electric magnet connected with the binding-post, and a rocking contact-plate having a binding-post for the reception of a wire in circuit with the magnet, a rock-shaft for supporting the plate, a fixed pawl depending from the rock-shaft and operated by the ratchet-wheel, and a contact-plate arranged at the lower end of the plate and adapted for contact with the point on the lever, substantially as specified.

4. In an actuating mechanism for clocks, the combination, with a rocking lever having a binding-post and a contact-point, and an electric terminal secured to the post, of a rock-shaft mounted above the lever, a depending rock-arm mounted on the shaft and carrying a yielding contact-plate, an oscillating pawl depending from the shaft, and a ratchet-wheel and means for operating the same in the path of the pawl, substantially as specified.

5. In an actuating mechanism for clocks, the combination, with the sides 1 and 2 and binding-sleeves 3, of the electro-magnet 4, supported by the rear side 1, the bearing 12, located below the magnet, the rocking lever 14, pivoted, as at 13, in the bearing and having the arm 15, the pole of the magnet forming a stop and having the threaded end 18, and adjustable nut 17, and means for temporarily magnetizing the magnet, substantially as specified.

6. In an actuating mechanism for clocks, the combination, with the rock-shaft 26, having the rock-arm 29, and binding-post 34, and the

terminal 31, connected therewith, of the slotted yielding contact-plate 32, the bolts 34, for adjusting the plate, and the rocking lever 14, having the contact-point 22, binding-post 20, 5 and the electrical terminal 21, substantially as specified.

In testimony that I claim the foregoing as

my own I have hereto affixed my signature in presence of two witnesses.

HERMAN THEODORE SCHLEGEL.
